Des. 191,694
Patented Nov. 7, 1961

191,694

COMBINED SIPHON AND DISPENSING CAP

Saul Blitz, Kings Point, N.Y., assignor to
R & L Draisin Company, Belleville, N.J.

Continuation of applications Ser. Nos. 57,399 and 57,401,
Sept. 1, 1959. This application Jan. 18, 1961, Ser. No.
63,767

Term of patent 14 years

(Cl. D2—3)

FIG. 1 is a side elevational view of a combined siphon and dispensing cap embodying my new design,

FIG. 2 is a top end view thereof,

FIG. 3 is a bottom end view thereof, and

FIGS. 4, 5, and 6 are side elevational, top and bottom plan views, respectively, showing a modified form of the combined siphon and dispensing cap embodying my new design shown in FIGS. 1, 2 and 3.

The dominant features of the design reside in the portions shown in full lines.

This application is a continuation of my earlier filed co-pending applications, Serial Nos. D. 57,399 and D. 57,401, filed September 1, 1959, now abandoned.

I claim:

The ornamental design for a combined siphon and dispensing cap, substantially as shown and described.
